DESIGN FOR A DRINKING STRAW OR SIMILAR ARTICLE

Julius Duberstein, New York, N. Y.

Application October 7, 1942, Serial No. 108,450

Term of patent 3½ years

To all whom it may concern:

Be it known that I, Julius Duberstein, a citizen of the United States of America, residing at New York, in the county of Kings and State of New York, have invented a new, original, and ornamental Design for a Drinking Straw or Similar Article, of which the following is a specification, reference being had to the accompanying drawing, constituting a part thereof.

Figure 1 is a front elevational view of a drinking straw or similar article showing my new design.

Figure 2 is a rear elevational view thereof.

Figure 3 is a top plan view thereof.

Figure 4 is an enlarged fragmentary developed view of the drinking straw shown in Figure 1.

Figure 5 is a fragmentary enlarged view of the strip forming the drinking straw shown in Figure 1.

I claim:

The ornamental design for a drinking straw or similar article, as shown.

JULIUS DUBERSTEIN.
